UNITED STATES PATENT OFFICE.

PATRICK B. DELANY, OF NEW YORK, N. Y.

TELEGRAPHY.

SPECIFICATION forming part of Letters Patent No. 373,968, dated November 29, 1887.

Application filed June 21, 1887. Serial No. 242,032. (No model.)

To all whom it may concern:

Be it known that I, PATRICK B. DELANY, of New York city, in the State of New York, have invented certain new and useful Improvements in Telegraphy, of which the following is a specification.

On long telegraph-lines—particularly underground or submarine cables—the speed of transmission is greatly reduced by the effect of the static charge. On such lines the best results have been obtained by the use of reverse currents. Even with reverse currents, however, serious obstacles are encountered because of the unequal duration of the impulses and the consequently unequal static charge and discharge. It is well understood that when a dash is made the charge of static is proportionally greater than when the dot is made, and that when a dot quickly follows a dash the effect of the discharge at the transmitting end is to partially obliterate the dot, while at the receiving end the current "tails" or runs out of the line so slowly as to bridge over the space between the dash and the weakened dot which comes after it.

In another application filed by me March 17, 1887, No. 231,302, I have shown a system of telegraphic transmission designed to remedy the defects above referred to. In that case, 30 by the manipulation of a Morse key, currents of alternating polarity, but equal duration, are thrown upon the line and received, either as dots or dashes, as the case may be, upon a polarized relay, the line being grounded at 35 both ends after the transmission of each impulse to eliminate the static currents from the circuit. The main parts of the apparatus shown in this case are substantially the same as those shown in my pending application 40 with the exception of the particular means shown for operating the instrument by the manipulation of a Morse key and the use of a condenser for neutralizing the static discharge, which features form the subject-matter of my 45 present invention. I do not therefore claim herein any subject-matter claimed in said pending application.

In the accompanying drawings, Figure 1 is a diagram view of one station or terminal of a 50 line equipped according to one form of my present invention, and Fig. 2 is a similar view

showing a different manner of connecting the condenser.

Insulated contacts *g h*, arranged in a circle, are connected in alternate series with the poles 55 of a battery, M B—that is, the alternate contacts *g* are connected with the — pole and the other contacts, *h*, with the + pole, the battery being split and grounded in the middle. Between the contacts *g h* and insulated therefrom 60 are arranged contacts *l* —, in this instance the latter contacts being all part of an insulated plate, L, which is grounded through the coils of a polarized relay, P R. A circuit-completing trailer, G, carried by a rotating spindle 65 centrally placed in the circular table of contacts and connected with the line M L through a brush and post, I, may be caused to traverse the contacts in such manner as to cross a segment, *g* or *h*, at each movement and pause 70 upon a relay-connected segment, *l*. Obviously, the successive movements of such a trailer, G, send impulses alternately from the the opposite poles of the battery M B, and such impulses must be of the same duration, 75 because they enter the line only during the movements when the trailer is passing over a contact, *g* or *h*. With similar apparatus at a 80 distant station at rest with the trailer on a contact, *l*, and the line therefore to relay, the polarized relay will respond to each impulse and the character of the signal—whether a dot or a dash—be determined by the time the armature is permitted to remain in one position, 85 the signals being produced, if desired, upon a sounder, S, in a local circuit controlled by the relay-armature.

The general construction and operation above described are the same as shown and described in my pending case above mentioned, 90 to which reference is made for more elaborate description.

My present invention, as above mentioned, relates, first, to the manner of operating the instrument by the Morse key, and, second, to 95 the use of a condenser for neutralizing the static.

In my improved arrangement the spindle carrying the trailer G is actuated mechanically directly from the key-lever, all intermediate circuits and magnets being dispensed with. The key A is shown as having adjust-

able stops *a* on each side of its pivot, and at its end is provided with toothed arms which alternately engage the teeth of a toothed wheel, *f*, on the spindle of the trailer after the manner of an ordinary clock-scapement. Each actuation of the key, either up or down, advances the trailer from one of the segments *l* across the face of a segment, *g* or *h*, and then permits it to pause upon the next segment *l*. The speed with which the trailer crosses a segment and the consequent duration of the impulse transmitted are practically uniform, and the character of the signal transmitted depends upon the length of time the key is held in a given position. Obviously the key may therefore be manipulated in the ordinary manner, and dots and dashes be received upon the distant relay.

To neutralize the static discharge arising from such alternate impulses, I employ a condenser, which may be arranged in various ways, two suitable and practical arrangements being shown in the drawings. In Fig. 1 the condenser *Cd* is shown as permanently connected in the line *l'* between the contacts *l* and the relay *P.R.* In Fig. 2 a switch, *V*, is interposed between the condenser and relay, so that the condenser may be connected to the relay or put direct to ground. In each case the condenser is shunted by an adjustable resistance, *Rh*, by means of which its operation may be regulated and controlled, or by which it may be entirely short-circuited, if desired, when receiving, for instance, under some circumstances. The trailer *G*, as stated, rests normally upon a relay-segment, *l*, as shown. Now, if the key be raised, the trailer is caused to move across a positive battery-segment, *h*, but in passing on to that segment the trailer bridges or touches it while it is still on the segment *l*, and the current from the positive pole of the battery charges the condenser at the same time that it flows to line. The charging of the condenser is repeated as the trailer passes from the positive-battery segment; but when the trailer rests entirely on the segment *l*, which it does after each impulse is transmitted, the charge from the condenser goes to line and neutralizes the static discharge. All this takes place while the key is being raised and held up. When it is depressed, the same operation occurs, except that the condenser and line are charged with a negative current. In some cases the shunt around the condenser might be omitted. Preferably condensers will be employed at each end of the line. In fact, both ends of the line may have instruments of identically the same style, and it has therefore been thought unnecessary to illustrate more than one terminal. Obviously the use of the condenser is not limited to the particular manner shown of transmitting the alternating impulses. As the transmitted currents are of uniform duration, and the resultant static similarly uniform, the condensers may readily be adjusted to completely eliminate static disturbances from the line. Very long

and ordinarily difficult lines may therefore be worked with facility and rapidity.

Instead of a condenser I might use electro- 70 magnets or other sources of electric energy.

I claim as my invention—

1. The combination, with a transmitter having contacts for connection with opposite poles of a source of electric energy, as set forth, and 75 a circuit-completer which traverses said contacts, and thereby transmits over the line currents of alternate polarity and equal duration, of a Morse key and a direct mechanical transmitter-operating connection between the key 80 and transmitter, whereby the circuit-completer is operated step by step to traverse said contacts by the manipulation of the key, substantially as set forth.

2. The combination, with the contact-bat- 85 tery, circuit-connections, and trailer, of the trailer-spindle, its toothed wheel, and a Morse key having a bifurcated end, which engages said wheel and causes the step-by-step rotation of the trailer as the key is operated, substan- 90 tially as set forth.

3. The combination of the alternate contacts *g h*, connected, respectively, with opposite poles of a source of electric energy, a trailer or circuit-completer connected with the 95 main line and traversing said contacts, whereby by message impulses of alternating polarity and equal duration are sent into the line, the intermediate contacts, *l*, also traversed by said circuit-completer, and a source of electric en- 100 ergy connected with the latter contacts, from which a neutralizing impulse is sent into the line after the transmission of each of said message impulses.

4. The combination of a transmitter having 105 contacts connected with opposite poles of a source of electric energy, and a circuit-completer which traverses said contacts, and thereby sends over the line currents of alternating polarity and equal duration, a Morse key, trans- 110 mittor-controlling devices interposed between the key and the transmitter, whereby when the key is depressed the transmitter is operated to send a message-current of one polarity, and when the key is raised to transmit a mes- 115 sage-current of equal duration but opposite polarity, and a source of electric energy and contacts from which a neutralizing impulse is sent into the line after each message impulse is transmitted. 120

5. The combination of the contacts *g h*; connected, respectively, to opposite poles of a source of electric energy, the intermediate contacts and the condenser connected therewith, the line and the circuit-completer connected 125 therewith, and the trailer-actuating devices and Morse key, by the manipulation of which the trailer is caused to pass from a condenser-connected contact across a contact, *g* or *h*, and pause upon a condenser-connected contact, 130 substantially as and for the purpose set forth.

6. The combination of a main line, a contact or contacts, *g*, connected with one pole of a source of electric energy, a contact or con-

tacts, *h*, connected with an opposite pole of a source of electric energy, a trailer or circuit completer connected with the line which traverses said contacts, a key, devices interposed 5 between the key and trailer whereby the latter is actuated step by step as the key is manipulated and caused at each movement to cross the face of a contact, *g* or *h*, thus sending currents of alternating polarity into the line, and 10 a source of electric energy and contacts from

which a neutralizing-current is sent into the line to neutralize the static effect after each transmission of a current, substantially as set forth.

In testimony whereof I have hereunto subscribed my name. 15

Correction in Letters Patent No. 373,968.

It is hereby certified that in Letters Patent No. 373,968, granted November 29, 1887, upon the application of Patrick B. Delany, of New York, New York, for an improvement in "Telegraphy," an error appears in the printed specification requiring correction, as follows: In line 85, page 2, the word "contact" should read *contacts*, and the hyphen thereafter should be stricken out and a comma inserted instead; and that the Letters Patent should be read with this correction therein that the same may conform to the record of the case in the Patent Office.

Signed, countersigned, and sealed this 20th day of December, A. D. 1887.
